UNITED STATES PATENT OFFICE.

WILLIAM GEO. DINGLE, OF LOS ANGELES, CALIFORNIA.

STREET-SWEEPING MACHINE.

SPECIFICATION forming part of Letters Patent No. 694,620, dated March 4, 1902.

Application filed March 14, 1901. Serial No. 51,202. (No model.)

To all whom it may concern:

Be it known that I, WILLIAM GEO. DINGLE, a citizen of the United States, residing at Los Angeles, in the county of Los Angeles and 5 State of California, have invented new and useful Improvements in Street-Sweeping Machines, of which the following is a specification.

The object of my invention is to provide a 10 machine of simple construction that may be operated by hand, and the same is hereinafter fully described, and illustrated in the accompanying drawings, in which—

Figure 1 is a perspective view of my machine. Fig. 2 is a side view of one of the shovels with the supporting parts of the frame in section. Fig. 3 is a cross-section on line 3—3 of Fig. 2. Fig. 4 is a view showing the manner of attaching the bristle to the frame of 20 the sweeping-brush. Fig. 5 is an edge view of two of the sprockets. Fig. 6 is a side view, partly in section, on line 6—6 of Fig. 5.

In the drawings, A is the axle of the machine, which is rotatively mounted in the 25 frame B. On one end of the axle is rigidly mounted driving-wheel C, and on the other end thereof is loosely mounted the other driving-wheel D and the driving sprocket-wheel E. In each end of the hub of the driving 30 sprocket-wheel is a conventional ratchet mechanism, (shown in detail in Fig. 6,) by means of which when the machine is pushed forward the driving-sprocket is locked fast to the axle and to the loose driving-wheel. The 35 purpose of having one of the driving-wheels loose on the axle and having sprocket mechanism to lock it fast to the driving-sprocket is that each driving-wheel may act independently, as in turning the machine around a 40 corner. The driving-sprocket is connected to sprocket-wheel F, affixed to the end of the sweeping-brush G, by sprocket-chain H, through which motion from the driving sprocket is imparted to the brush. The 45 brush is rotatively mounted in the front end of the brush-supporting arms I, which are pivotally connected to the frame by bolts J, so that the brush may be turned up into the center of the machine when transporting it 50 from one place to another. When in an operative position, as shown in Fig. 1, these supporting-arms rest on the regulating slotted

bars K, which keep the brush at the proper elevation above shovels L. These bars may be adjusted to lower the brush as the bristles 55 G' thereof wear away, and thereby enable the bristles to be almost entirely worn away before being discarded. These bristles are held in the brush between two longitudinal bars G'' and G''', one of which is affixed to the spider 60 G''', the bars being held together by screws or bolts, thereby rendering the removal and replacement of the bristles an easy matter.

L are shovels mounted in the front part of the frame in the rear of the sweeping-brush, 65 over which the dirt is swept, and are adapted to contact with the surface of the street being swept to scrape up or loosen dirt therefrom which it is desired to have removed therefrom. There are a plurality of these shovels, which 70 are spring-pressed downward to make better contact with the street-pavement when it is uneven. The shank L' of each shovel is flattened to form a frustum of a wedge along that portion to which the shovel-blade is attached and passes through a dovetail groove in one of the cross-bars B' of the frame, as 75 shown in Fig. 3. The shank is slightly curved, and the other end passes through cross-bar B'', which permits each shovel to move backward and upward, so that it may pass over any slight solid projection in the surface being swept, and they are returned to their normal position by spring M after the obstruction is passed. As the machine is pushed 80 forward the dirt is swept up over the shovels into the removable dust-pan N, which when filled is removed from the frame, emptied, and replaced. If the machine should reach a pile of dirt too large to be swept up by the 85 brush as driven by the wheels, the operator pushes the brush up into engagement with the dirt and by turning crank O operates the brush through connecting mechanism to sweep the dirt into the dust-pan. This connecting mechanism is described as follows: Crank O is rigidly affixed to a rod P, which 90 passes through the hollow rear end member of the frame. On the other end of rod P is rigidly affixed sprocket-wheel R, which is operatively connected by chain T with sprocket-wheel S, mounted on the hub of the driving sprocket and connected thereto by ratchet mechanism similar to that which connects the 95 100

driving-sprocket with the axle, but working in the reverse direction.

Having described my invention, what I claim as new, and desire to secure by Letters 5 Patent, is—

1. A street-sweeping machine, comprising a frame having an axle rotatively mounted therein; two driving-wheels on said axle, one of which is loosely mounted, and the other rig-10 idly mounted on said axle; a driving sprocket-wheel loosely mounted on said axle; ratchet mechanism intermediate the axle and the driving-sprocket and the loose driving-wheel and the driving-sprocket, adapted, when the 15 machine is pushed forward, to lock the driving-sprocket to the axle and to the loose driving-wheel to cause the rotation of the driving-sprocket, and when pulled backward to unlock the driving-sprocket from the axle and 20 the loose wheel; a sweeping-brush revolubly mounted in the forward end of the machine, having a sprocket-wheel connected thereto; a sprocket-chain connecting said last sprocket with the driving-sprocket; shovels mounted 25 in the front end of the frame adapted to be moved backward and upward independently of each other, and a removable dust-pan.
2. In a street-sweeping machine, means to impart motion to the sweeping-brush inde-30 pendent the main driving-wheels, comprising a sprocket-wheel rotatively mounted on the rear part of the frame, having means to cause its rotation; a main driving sprocket-wheel loosely mounted on the axle of the machine; 35 a sprocket-wheel mounted on the hub of the main driving-sprocket, having sprocket mechanism adapted to lock the two sprocket-wheels

together when driven in one direction, and unlock them when driven in the reverse direction; a sweeping-brush mounted in the front 40 part of the frame; a sprocket-wheel on the axle of the sweeping-brush and sprocket-chains connecting said sprocket-wheels, in combination with a frame; an axle mounted in said frame, and supporting-wheels on said axle, 45 as described herein.

3. In a street-sweeping machine, having a frame and driving-wheels adapted to drive the sweeping-brush, the combination of a sweeping-brush revolubly mounted in the 50 front end of the frame and means to revolve said sweeping-brush independently of the driving-wheels, comprising a sprocket-wheel affixed to the brush, a sprocket-chain connecting said sprocket-wheel with the driving- 55 sprocket; a driving-sprocket loosely mounted on the axle of the machine; a sprocket-wheel on the hub of the driving-sprocket; ratchet mechanism between said hub and said wheel, adapted to lock the two when the sprocket-wheel on the hub is rotated in one direction, and unlock it therefrom when rotated in the reverse direction; a sprocket-chain connecting the sprocket-wheel on the hub of the driving-sprocket with a sprocket-wheel on a rod; a 60 rod revolubly mounted in the rear member of the frame, and a crank on the end of said rod.

In witness that I claim the foregoing I have hereunto subscribed my name this 6th day of March, 1901.

WILLIAM GEO. DINGLE.
